METHOD OF FORMING BOXES OR BOX PARTS WITH CURVED BOTTOMS

Filed Feb. 8, 1930

UNITED STATES PATENT OFFICE

JOHANNES SCHMIEDEL, OF DRESDEN, GERMANY, ASSIGNOR TO THE FIRM "UNIVERS-
SELL" CIGARETTENMASCHINEN FABRIK J. C. MÜLLER & CO., OF DRESDEN, GER-
MANY

METHOD OF FORMING BOXES OR BOX PARTS WITH CURVED BOTTOMS

Application filed February 8, 1930, Serial No. 426,887, and in Germany February 26, 1929.

This invention relates to the production of boxes with arched or shaped bottoms.

In the production of boxes, particularly boxes provided with lids and provided with a neck insert it is usual to arch the lid or give it a concave form and also to provide it with impressions.

It has been proposed to form the boxes first with a flat base and a flat lid, to open them after completion and in this position to deliver them to a stamping press which subsequently produces the convexity of the lid and the necessary impressions. This known method has the disadvantage that it involves changing the shape of the already completed box an operation which with fragile articles does not afford a satisfactory product.

It has moreover, been proposed to curve the portion of the blank which will be the bottom before producing the box and to apply the blank so shaped to the finished lower part and to form it.

Great difficulties arise under this method because the shaping of the lid on the neck insert is only possible naturally if the lid is of thin paper and the neck insert of strong cardboard.

The present method consists in shaping the box blank with the aid of a forming block curved on the corresponding side wall in a shaping channel first with a flat bottom surface and then shaping the blank embracing the forming block in the shaping channel or in a passage around the curved portion of the forming block by means of a shaped die passing through the corresponding opening in the wall of the channel. In apparatus for carrying the method into effect there is arranged in the feed channel which serves to receive the forming block provided with the folded work, a shaped die moving transversely of the longitudinal direction of the channel which presses the work as it comes in front of it over the curved portion of the forming block.

The invention is illustrated in the accompanying drawings in which Fig. 1 is a vertical longitudinal section through the apparatus, Fig. 2 is a vertical cross section on the line 2-2 of Fig. 1, while Fig. 3 illustrates in perspective a forming block suitable for the purpose.

Referring to the drawings, the neck strip Za disposed above the junction of the two blanks Zo and Zu is pushed into the shaping channel 2 along with the blanks by means of a forming block F pushed downwards by the plunger 1. The plunger 3 which is retracted as the plunger 1 advances serves as an abutment. While the blanks are bent upwards at right angles on the upper edges of the shaping channel 2, the sides are pressed against the forming block by the folding bars 2'. After the plunger 3 has returned to the position shown in dotted lines in Fig. 1 the plunger 4 moves forward and pushes the forming block with the work thereon into the channel 5. As a result the two ends of the neck strip which still project are pressed against the forming block by the bending fingers 6 on the plunger 4 and the stationary bending finger 7 arranged in front of the channel 5.

The bars 8 arranged at the forward end of the channel 5 press the still projecting upper side edges of the blank against the forming block.

The curved die 9 now passes through an opening in the wall of the channel 5 and presses the bottom of the work over the curved portion of the forming block. It should be noted that in positioning the blanks between the forming block F and the plunger 3 in the shaping channel a gap must be left at the junction of the two side edges. This is easily provided by means of stops which detain the blank Zu somewhat. At the end of the channel 5 the work is led by means of the plunger 10 into a channel 11 from which

it is fed to known means for applying a binding strip or fastening the corners.

The movement of the various elements is effected as follows:—

5 The plunger 1 is supported on the extension 13' of the machine frame 13 in a guide 12. The movement of the plunger is effected as follows:—

10 A lever 14 is pivotally mounted at 15 to said extension 13' and by means of forked arm 15' engages a projection 16 on the plunger shaft. The free end of lever 15 is pivotally connected to a link 17 which latter is pivotally connected to one end of a lever 18. 15 Lever 18 is pivoted intermediate its ends to the machine frame as at 19. The free end of lever 18 has a roller 20 thereon which tracks a cam 21 keyed to a shaft 22 which latter has also a gear 23 thereon driven in 20 a manner to be presently described.

Folding member 6 which is slidably mounted on the die shaft 4 is actuated as follows. A link 42 is pivotally connected to member 6 and to one end of a lever 40.

25 Lever 40 is pivotally connected to the machine frame at 41. The other end of lever 40 is pivotally connected to a link 39 which is also pivotally connected to a lever 38. Lever 38 is pivoted to the machine frame at 29. Intermediate the ends lever 38 is provided with a cam roller 37, which tracks a cam 36 keyed on a shaft 25. A gear 24 on shaft 25 meshes with gear 23 for a purpose to be presently described.

30 35 Plunger 4 which is slidably supported in a guide 35 is actuated as follows:—

A link 34 is pivotally connected to the plunger and to one end of a lever 31. Lever 31 is pivotally connected to the machine frame at 32. The free end of lever 31 is pivotally connected to a link 30 which is pivotally connected to a lever 28. Lever 28 is pivoted to the machine frame at 29. Intermediate its ends said lever is provided with 45 a roller 27 which tracks a cam 26 also keyed to shaft 25.

Plunger 3 which is slidably supported in a guide 51 is actuated as follows:—

50 A lever 48 pivoted at 49 to the machine frame, with its end 48' engages a projection 50 on plunger 3. A link 47 is pivotally connected to lever 48 intermediate the ends of the latter. Said link also is pivotally connected to a lever 45 which latter is pivotally mounted to the machine frame at 46. Intermediate its ends lever 45 is provided with a roller 44 which tracks a cam 43 also keyed on shaft 25. A spring 52 fastened at 53 to the machine frame and to the plunger 3 on 55 an extension 3' thereof tends to maintain the plunger in raised position at all times.

Plunger 10 is slidably supported in a guide 64 mounted on an extension 13" of said frame 13. Said plunger is actuated as follows:—

55 A lever 61 is pivotally mounted at 62 to

extension 13". One end of said lever is forked at 61' and engages a projection 63 on plunger 10. A link 60 is pivotally connected to the other end of lever 61 and to one end of a lever 58. The latter is pivoted to the machine frame at 59. Intermediate its ends, lever 58 is provided with a cam roller 57 which tracks a cam 56 keyed to a shaft 55. Also keyed to shaft 55 is a gear 54 which meshes with gear 24. A bevel gear 65 is also keyed to shaft 55 and may mesh with a suitably supported bevel gear 65' on a shaft 66. A second bevel gear 67 keyed to shaft 66 meshes with a gear 67' on the main drive shaft 68 to which a suitable power source (not shown) may be connected. Since gears 23, 24 and 54 mesh, all the cams are driven from a common source.

In Fig. 2 of the annexed sketches is shown the holding and feeding means for the box blanks *Zo* and *Zu* and the actuating means of die 9.

Holders 82 and 88 respectively are mounted on the machine frame 13 and the blanks *Zo* and *Zu* are respectively fed from the piles therein by the feeders 81 and 87. The feeders are actuated as follows:—

A link 80 is pivotally connected to feeder 81 and to one end of a lever 78 which is pivoted at 79 to the frame 13. The free end of lever 78 is provided with a roller 77 which tracks a cam 76 rotatably borne on a shaft 70. A link 86 is pivotally connected to the feeder 87 and one end of a lever 84. The latter is pivotally connected to the frame 13 at 85. A link 83 is pivotally connected to the free end of lever 84 and also pivotally connected to lever 78 at 83'. Movement of lever 78 therefore serves to actuate both feeders 81 and 87.

Die 9 which is supported in a guide 94 is actuated as follows:

A link 93 is pivotally connected to said die and one end of a lever 91. The latter is pivoted at 92 to frame 13 and at its free end has a roller 90 which tracks a cam 89. The latter is keyed to shaft 70. Shaft 70 through suitable gearing is driven from shaft 68.

I claim

1. Apparatus for forming boxes or box parts with curved bottoms including a forming block said forming block formed with a curved portion, a feed channel serving to receive the forming block provided with the folded box, said feed channel formed with an opening, and a shaped die movable transversely of the longitudinal direction of the channel and adapted to press the box around the said curved portion of the forming block.

2. A method of forming a box having a curved face from two box blanks comprising folding said blanks about a forming block having a curved face to form a flat faced box and then curving the portion of the so formed

ed box adjacent said curved face of said block to conform to the shape thereof while on said block.

3. A method of forming a box part having a curved face from a box blank including the step of folding said blank about a forming block having a curved face to form a flat faced box and then curving the portion of the so formed box adjacent the curved face of said block to conform to the shape thereof while on said block.

In testimony whereof I affix my signature.
JOHANNES SCHMIEDEL.
